IRONER

John J. McCabe, Cleveland, Ohio, assignor to
 The Apex Electrical Manufacturing Company,
 Cleveland, Ohio, a corporation of Ohio

Application April 6, 1933, Serial No. 664,765

14 Claims. (Cl. 38—59)

This invention relates to ironing machines and in particular machines of the type employing a rotatable padded member and a heated member to form the ironing elements of the machine, one 5 of the same being laterally movable with respect to the other for effecting ironing pressure between the ironing elements.

Among the objects of this invention relating to ironing machine constructions are the following: the provision of a highly efficient mechanism 10 of low power consumption whereby a small power unit may be used; the provision of an improved safety release for quickly separating the ironing members of the machine; the provision of an improved means for controlling and effecting the rotation of the roll; the provision of an improved means for laterally shifting the rotatable roll; the provision of an improved means for providing for resilient ironing engagement between the 15 padded member and the heated member; the provision of an improved form of ironer shoe construction; the provision of an improved roll supporting member; and the provision of an improved shoe support and safety release.

With these and other objects in view, the invention consists in the novel construction, arrangement and combination of parts, hereinafter illustrated and described in some of its embodiments in the accompanying drawings, and particularly 20 pointed out in the appended claims.

In the drawings Figure 1 is a sectional view taken on broken line 1—1, Figure 2 of an ironing machine illustrating one mode of practicing the invention; Figure 2 is a sectional view taken on 25 broken line 2—2, Figure 1 showing the elements of the machine in ironing position; Figure 3 is a sectional view taken on broken line 3—3, Figure 1; Figure 4 is a detail view similar to Figure 2 and showing the roll and shoe separated from 30 each other; Figure 5 is an enlarged detail view of the ironer clutch; Figure 6 is a sectional view taken on line 6—6, Figure 5; Figure 7 is a detail perspective view of some of the mechanism provided to control the rotation of the roll; and 35 Figure 8 is a sectional view taken on line 8—8, Figure 3 showing the details of the safety release for the ironer shoe.

The machine shown in the drawings comprises a padded roll 1 and a heated shoe 2, the two 40 operating with each other to form the ironing elements of the machine. The roll is supported from a gear case 3 and the shoe is carried by a pair of standards 4, one of which is provided at each end of the shoe. The gear case 3 and the 45 standards 4 are carried by a supporting base 5,

the underside of which supports a motor 6 which is provided for operating the machine and the upper side of which provides a work receiving surface.

This machine is of the type in which a rotatable 5 roll is bodily movable toward and away from a heated ironing member and the elements of the mechanism for effecting both the rotation and the lateral movement of the roll are housed, some within the gear case 3 and others within the roll 10 itself. The roll may be formed from a sheet metal cylinder 7, which is journaled for rotation about a generally oval supporting tube 8, secured at one end in a hollow inwardly projecting boss 10 formed in the gear case 3. 15

The end of the tube remote from the gear case is unsupported and it permits the provision of what is known as a full open end ironer for facilitating the use and operation of the machine in performing the more difficult ironing operations, 20 as for example the ironing of men's dress shirts and the ironing of ruffled articles of wearing apparel.

The mechanism in the case 3 is operatively connected to the motor 6 by means of a belt 11 and 25 the associated motor and mechanism pulleys 12 and 13 respectively. The pulley 13 is carried by a shaft 14 journaled at one end in a plain bearing 15 formed in a boss 16 carried by the gear case 3. The other end of the shaft is journaled in an anti-friction bearing 17 carried in a wall of the gear housing, an oil seal 18 being provided outside the anti-friction bearing to prevent the escape 30 of lubricant from the gear case. A cap 20 holds the seal in place. 35

A worm 21 carried by the shaft 14 meshes with a worm gear 22. The worm gear is secured by means of a pin 23 to a short shaft 24 which is journaled at one end in a bearing formed in a boss 25 of the gear case. The other end of this 40 shaft is journaled in a supporting member 26 which is secured at its opposite ends by the bolts 27 to the gear case. The shaft 24 extends through a wall of the gear case and is provided with an oil seal 28 of similar construction to the worm shaft seal to prevent the escape of lubricant at this point. The worm gear 22 may conveniently be formed from a standard spur gear having the center portion 30 of the opposite faces of each 50 tooth hobbed a slight amount for the accommodation of the worm 21, the end parts of the gear teeth being unhobbed.

A gear 31 journaled on a stub shaft 32 carried by a member 33 mounted for movement about the 55

axis of a shaft 34, is provided for selective meshing engagement with the worm gear 22. When the gears 22 and 31 are in meshing engagement the faces of the teeth of the gear 31 contact only with the unhobbed portions of the teeth of the gear 22, the teeth of these gears being of sufficient width to quietly and efficiently take the load imposed upon them. This arrangement permits the use of a worm gear both as a reduction gear and as a driving gear.

To one side of the gear 31 there is fixed a pinion 35 which is coaxial therewith. The pinion 35 meshes at all times with a gear 36 which is secured to the shaft 34 by means of the pin 37, the pinion being maintained in mesh with the gear 36 by means of the supporting member 33 which as has been previously stated is journaled for oscillation about the axis of the gear 36 by mechanism which will be described in detail presently.

The shaft 34 is journaled in a suitable bearing member 38 carried within the tube 8 and it is provided with a portion which extends beyond the bearing member a slight distance. A slotted coupling 40 is pinned at 41 to the extended portion of the shaft. A roll driving shaft 42 is received in the coupling member 40. This shaft is provided with a pin 43 which is received within the slots of the coupling and it constitutes therewith a universal joint for one end of the shaft 42. The opposite end of the roll driving shaft is provided with a similar pin 43 which is received within the slots of the coupling member 44. This coupling member is journaled for rotation in a bearing 45 formed intermediate the length of a roll supporting member 46 and at its opposite end the end coupling member 44 is fixedly secured to an end cap 47 of the roll by means of a bolt 48.

The member 46 is oscillatably supported by a pin 49 which is carried by the bracket 48 of a member 50 fixedly carried on the outer end of the tube 8. A second pin 51 is carried in a rigid manner by a hollow boss 52 which extends into the gear case 3. An annular disk-like member 53 carries an eccentric bearing member 54 which is journaled to the pin 51 for movement about the pin axis. This member is provided at its outer edge with a bearing member 55 which engages with a bearing 56 carried by the sheet metal drum 7 of the roll.

The members 46 and 53 are provided with suitable openings 57 and 58 for receiving the ends of a rod 60. This rod is pinned at 61 to the member 53 and at its opposite end it is formed with a rounded portion 62 for permitting relative movement between the rod and the member 46 so that one end of the roll may shift with respect to the opposite end for applying uniform ironing pressure to articles of non-uniform thickness.

The axis of the roll is shifted by means of a rod 63 secured in the ends of a pair of crank arms 64 and 65, the opposite ends of which are mounted for movement in suitable bearings 66 and 67, one of which is provided in the member 50 and the other of which is provided in a member 68 carried by the inner end of the tube 8. The crank arm 64 is provided with a pin 70 which is journaled in the bearing 66.

The crank arm 65 is fastened to a shaft 71 which projects through the bearing 67 and extends beyond the end of the roll and into the space defined between a gear case cover 72 and the side wall 73 of the gear case. This end of the shaft 71 carries a crank member 74. A connecting rod 75 is secured to this member. The

connecting rod is journaled on a pin 76 carried by the crank member 74 and at its opposite end it is journaled on a pin 77 carried by a plate 78 driven member of a clutch construction which is supported on the shaft 24.

The clutch mechanism is adapted for rotative movement by steps of substantially one hundred and eighty degrees and it serves to shift the connecting rod 75 and its associated members to one or the other of the two predetermined positions corresponding to the positions of the roll illustrated in Figures 2 and 4. The movement of the member 63 is transferred to the roll by means of the springs 80 and 81, the opposite ends of which are secured to the rods 60 and 63. The movement of the rod 60 is transferred to the members 46 and 53 and in this way the roll is shifted into resilient pressing engagement with the shoe 2.

The details of the clutch construction are best illustrated in Figures 5 and 6. The driven member 82 of the clutch is received within a cup-shaped housing member 83 which is pinned at 84 to the shaft 24, the cup-shaped member 83 constituting the driving part of the clutch. The driven part 82 of the clutch has the plate member 78 fixedly secured thereto. This plate member as has been stated, carries the bearing pin 77 of the connecting rod 75.

Oppositely acting cam faces 85 and 86 are formed in the driven member of the clutch. 30 Rollers or spheres 87 and 88 are fitted in the space between the cam faces 85 and 86 and the rim 90 of the driving clutch member 83. Springs 91 and 92 serve to urge the rollers into driving engagement with the interacting clutch parts. The driven member 82 of the clutch is provided with a bearing 93 for freely receiving the outer end of the shaft 24.

An operating member 94 is journaled on the bearing 93. This member comprises an arm having an inwardly extending finger 95 for engaging the roller 88 and it projects beyond the rim of the clutch part 83 where it has a second finger 96. The second finger is adapted to engage with stops 97 and 98 carried by the ends of bell cranks 45 100 and 101 which are pivoted at 102 and 103 to the gear case 3. The opposite ends of the bell crank members are articulated to each other by means of a pin 104 which is engaged by a control member 105 extending at its lower end below the 50 gear case.

The member 105 is pivoted at 106 to a lever 107 which is pivoted at 108 to a bracket 110 carried by the base member 5 of the frame of the machine. The free end of the lever 107 may be connected to any suitable manual foot or knee-operated controlling member as for example a rod 111 which extends from one end to the other of the machine at a point just beneath the supporting base 5. When this form of construction 60 is used a lever and bracket similar to the lever 107 and bracket 110 are provided for the rod 111 at the end of the machine remote from the gear case.

The bell cranks are provided with bent-over 65 portions 112 and 113 which provide stops to limit their inward movement. A spring 114 is provided to urge the bell cranks to the position shown in Figure 2. A nut 115 engaging the outer end of the shaft 24 is provided for holding the clutch 70 parts in assembled relation.

The plate 78, carried by the driven member 82 of the clutch, is provided with a cam face 116 which extends over the rim 90 of the driving clutch part 83. This cam member engages with 75

an arm 117 carried by a shaft 118 which traverses the wall 73 of the gear case and which is journaled in a boss 120 formed thereat. The inner end of this shaft is provided with a second arm 121 which engages with the gear supporting arm 33. The tooth reactions between the gears 22 and 31 and 35 and 36 tend to maintain the gears 22 and 31 in mesh. The member 121 provides a stop for holding the gear 31 in proper position 10 when it is in mesh with the gear 22.

The function of the aforesaid elements is to lift the gear carrying arm 33 and to disengage the gears 22 and 31 when the clutch member 78 is in the position shown in Figure 4, which corresponds to the inoperative position of the machine. When the clutch parts are rotated approximately one hundred and eighty degrees from the position shown in Figure 4 they assume a position corresponding to the operative 20 position of the machine as illustrated in Figure 2, whereupon the cam member 116 is moved away from the arm 117 allowing the gear carrying member 33 to assume the position shown in Figures 1 and 3, in which position the roll and 25 shoe are in contact with each other and the roll is slowly rotated by means of the motor 6 and the gears 21, 22, 31, 35 and 36.

The clutch stops 97 and 98 are arranged so that in both of the stopped positions of the 30 clutch the springs 80 and 81 transmit a force by way of the connecting rod 75 and the other associated elements, tending to continue the rotation of the driven clutch part after the disengagement of the roller 88. This serves to force 35 the roller 88 to a fully retracted position and prevent friction between the roller and the driven and driving clutch parts. Further rotation of the driven clutch part by the springs 80 and 81 is prevented by the member 94 which is 40 held in place by either one of the stops 97 or 98.

As a means for independently controlling the rotation of the shoe there is provided a slideable rod 122 accessible from the exterior of the machine and provided with a handle 123. When 45 this rod is moved upwardly it shifts an operating arm 124, rigid with the arm 117, thereby disengaging the gears 22 and 31 and preventing the rotation of the roll by the power means. In this position of the roll drive, the roll can be 50 freely rotated by hand in either direction and its shifting mechanism may be operated for moving the roll toward and away from the shoe for pressing and other operations.

The outer end of the gear carrying arm 33 55 carries a spring 125 which engages with a stop 126 carried by the wall of the gear case. These elements are provided for the purpose of limiting the upward movement of the gear 31 and its supporting arm 33.

60 The supporting standards 4 for the shoe may be formed from metal stampings and they are each provided at their upper ends with a bushing 127 in which is rotatably mounted the cylindrical block 128. The ironer shown is provided 65 with an offset portion 130 at each end thereof. The end portions of the shoe are pivotally and eccentrically connected by means of bolts 131 to the members 128. Bolts 132 are used to hold the members 128 in place.

70 The members 128 are connected to each other by means of a rod 133 which extends above the upper edge of the shoe and around the outer end parts thereof. By means of the rod 133 the shoe can be moved to a position away from and 75 behind the roll for cleaning and other purposes.

This shoe release is also provided for safety purposes for quickly releasing the shoe from the roll in case of accident as where a person would accidentally get their fingers or clothing between the roll and the shoe during the operation 5 of the machine.

The arms 4 each carry stops 134 and 135 for the end portions of the rod 133. Suitable stops 136 and 137 cooperating with the member 130, are provided by the member 128 for limiting the 10 movement of the shoe about the bearing provided by the bolts 131.

The shoe construction herein shown comprises a heated face plate 138, the upper end of which is turned over as shown at 140. An electric resistance heating element 141 is carried by the shoe. Suitable heat insulating material 142 is provided behind the heating element and a cover 143 having one end received beneath the turned over part of the shoe is secured in a removable 20 manner by means of studs 144 carried at the rear of the plate 138 and nuts 145. This form of shoe construction is inexpensive to build and is easy to assemble and to take apart for servicing or other reasons. 25

Certain details such as the wiring connections and switches have been omitted from this disclosure as such elements are well understood and they do not by themselves form a part of the present invention. 30

Furthermore it is to be understood that the particular forms of apparatus shown and described, and the particular procedure set forth are presented for purposes of explanation and that various modifications of said apparatus and procedure can be made without departure from this invention as described in the appended claims. 35

Having thus described my invention what I claim is: 40

1. In an ironing machine, ironing instrumentalities comprising a heated shoe with elements fixed adjacent to the ends thereof, means for heating said shoe, a pair of supporting standards, members journaled in said standards for carrying said shoe, means for pivotally and eccentrically connecting the fixed elements of said shoe to said members, and a handle for rotating said members for moving said shoe into ironing position and for bodily displacing it therefrom. 45

2. In an ironing machine, cooperating ironing elements comprising a padded element and a heated shoe, means for heating said shoe, and a support for said shoe comprising a pair of spaced standards, a member journaled in one end of each of said standards, a cross bar extending above the top of said shoe connecting said members to each other and operable for rotating the same about their axis, shoe supporting means pivotally connecting the end parts of said shoe 60 eccentrically to said members whereby said shoe may be brought into and out of cooperative relation with said padded ironing element, and stops provided on said members cooperating with a fixed part of said shoe for limiting the movement of said shoe about said members. 65

3. In an ironing machine, cooperating ironing elements comprising a padded element and a heated shoe, means for heating said shoe, and a support for said shoe comprising a pair of spaced standards, a member journaled in one end of each of said standards, a cross bar extending above the top of said shoe connecting said members to each other and operable for rotating the same about their axis, shoe supporting means for piv- 70

totally connecting the end parts of said shoe to said members eccentrically thereof whereby said shoe may be brought into and out of cooperating relation with said padded ironing member, stop 5 means rigid with one of said members for limiting the movement of said shoe about its pivoted connection and stop means rigid with one of said standards in the path of said cross bar for limiting the movement of said members in said standards 10 ards.

4. In an ironing machine, ironing instrumentalities comprising a heated shoe having an offset member projecting rearwardly therefrom, means for heating said shoe, a supporting member for said shoe, a rotatable member journaled in said supporting member, pivotal connections between the offset member of said shoe and said rotatable member and arranged eccentrically of the latter, means for turning said rotatable member 15 about its axis for displacing said shoe from ironing position, and cooperating stop means carried by said rotatable member and shoe for limiting the movement of said shoe about its pivotal connections.

5. In an ironing machine, cooperating ironing elements comprising a padded member and a heated member, means for heating said heated member, a support for said padded member, and a support for said heated member comprising a 20 standard, a rotatable member journaled in said standard, means pivotally connecting said heated member to said rotatable member eccentrically of the axis thereof, means for shifting said heated member about the axis of said rotatable member 25 for moving said heated member from ironing position, and stop means carried by said rotatable member and engageable with a part fixed to said heated member for limiting the movement of said heated member about its pivotal connection 30 with said rotatable member.

6. In an ironing machine, cooperating ironing elements comprising a padded member mounted for rotation about a horizontal axis and a heated member alongside said padded member, power 45 means for effecting pressing engagement between said members, means for heating said heated member, a support for said padded member, and a support for said heated member comprising a standard, a rotatable member journaled in said 50 standard for movement about an axis parallel to the axis of said padded member, means pivotally connecting said heated member to said rotatable member eccentrically of the axis thereof, means for shifting the pivotal connection of said heated 55 member about the axis of said rotatable member for moving said heated member from ironing position, and stop means carried by said standard and engageable with a part fixed to said last named means for limiting the movement thereof.

7. In an ironing machine, in combination, cooperating ironing members comprising a padded rotatable roll and a heated member, means for supporting said heated member alongside of said roll, means inside said roll comprising a flattened, non-circular tube and roll bearings pivotally carried eccentrically of the roll axis for supporting said roll for rotative and bodily movement about 70 and relative to said tube, and power means, including driving elements inside said tube, for rotating said roll and means comprising a crank member operatively connected to said ball bearing and pivoted from a point closely adjacent to one of the wider sides of said tube and substan-

tially coinciding with the medial line thereof for moving said roll into pressing contact with said heated member, the major cross-sectional dimension of said tube being substantially in line with the resultant of the reacting forces between said ironing members when they are in pressing contact with each other.

8. In an ironing machine, in combination, cooperating ironing members comprising a padded rotatable roll and a heated member, means for heating said heated member, means for supporting said heated member alongside of said roll, means inside said roll comprising a flattened, non-circular tube and roll bearings pivotally carried eccentrically of the roll axis for supporting 15 said roll for rotative and bodily movement about and relative to said tube, and power means, including a driving shaft in said tube, for rotating said roll and means inside said tube comprising a crank member operatively connected to said roll bearing and pivoted from a point closely adjacent to one of the wider sides of said tube and substantially coinciding with the medial line thereof for moving said roll into pressing contact with 20 said heated member, the major cross-sectional dimension of said tube being in the same general direction as that of the bodily movement of said roll.

9. In an ironing machine, in combination, cooperating ironing members comprising a padded rotatable roll and a heated member, means for heating said member, means for supporting said heated member alongside of said roll, means inside said roll comprising a rigid, flattened, non-circular supporting tube and roll bearings pivotally carried by a fixed part of the machine eccentrically of the roll axis for supporting said roll for rotative and bodily movement about and relative to said tube, power means, including a driving shaft in said tube, for rotating said roll and means comprising a crank member operatively connected to said roll bearing and pivoted from a point closely adjacent to one of the wider sides of said tube and substantially coinciding with the medial line thereof for moving said roll into 40 pressing contact with said heated member, the major cross-sectional dimension of said tube being substantially in the same general direction as that of the bodily movement of said roll, and means including a removable threaded member 45 accessible from the exterior of said roll for detachably securing said roll in place and for connecting it to its driving shaft.

10. In an ironing machine in combination, ironing members comprising a padded rotatable roll and a heated member, means for supporting said heated member alongside of said roll having a part therebelow providing a work receiving surface for ironed articles, means for heating said heated member, means for supporting said roll solely from one end thereof, said roll supporting means comprising a gear case and a rigid member extending laterally therefrom and into said roll, said gear case having its lower portion laterally offset in a direction away from said shoe, and power means, including gearing in said gear case, for rotating the roll and moving one of said ironing elements into pressing engagement with the other, said power means and the means for supporting said ironing members being configured and disposed so as to provide on the work receiving surface an unobstructed space of substantial width at and outwardly beyond the end of the roll adjacent to said gear case for the accommodation of articles ironed 70

at this end of the roll whereby such articles are not subjected to excessive wrinkling as they lie on the work receiving surface.

11. In an ironing machine in combination, 5 ironing members comprising a padded rotatable roll and a heated member, means for supporting said heated member alongside of said roll having a part therebelow providing a work receiving surface for ironed articles, means for heating 10 said heated member, means for supporting said roll solely from one end thereof, said roll supporting means comprising a gear case and a supporting member extending laterally therefrom and into said roll, said gear case having its lower 15 portion laterally offset in a direction away from said shoe, and power means, including gearing in said gear case, for rotating the roll and for moving it into pressing engagement with said heated member, said power means and the means for 20 supporting said ironing members being configurated and disposed so as to provide on the work receiving surface an unobstructed space of substantial width at and outwardly beyond the end of the roll adjacent to said gear case for the accommodation of articles ironed at this end of the roll whereby such articles are not subjected to excessive wrinkling as they lie on the work receiving surface.

12. In an ironing machine in combination, 30 ironing members comprising a padded rotatable roll and a heated member, means for supporting said heated member alongside of said roll having a part therebelow providing a work receiving surface for ironed articles, means for heating said heated member, means for supporting said roll solely from one end thereof, said roll supporting means comprising a gear case and a roll supporting member extending laterally therefrom and into said roll, said gear case having a rounded upper portion coaxial with the roll, and of smaller diameter than that of the roll and a portion therebeneath having a width not exceeding the diameter of the roll and power means, including gearing in said gear case, for 35 rotating the roll and moving one of said ironing elements into pressing engagement with the other, said power means and the means for supporting said ironing members being configurated and disposed so as to provide on the work receiving surface an unobstructed space of substantial width at and outwardly beyond the end of the roll adjacent to said gear case for the accommodation of articles ironed at this end of the roll whereby such articles are not subjected to excessive wrinkling as they lie on the work receiving surface.

13. In an ironing machine in combination, ironing members comprising a padded rotatable roll and a heated member, means for supporting said heated member alongside of said roll having a part therebelow providing a work receiving surface for ironed articles, means for heating said heated member, means for supporting said roll solely from one end thereof, said roll supporting means comprising a gear case and a rigid member extending laterally therefrom and into said roll, said gear case having its lower portion laterally offset in a direction away from said shoe, and power means, including gearing in said gear case and a motor therebelow for rotating the roll and moving one of said ironing elements into pressing engagement with the other, said gearing comprising a flexible driving element and a worm gear, said power means and the means for supporting said ironing members being configurated and disposed so as to provide on the work receiving surface an unobstructed space of substantial width at and outwardly beyond the end of the roll adjacent to said gear case for the accommodation of articles ironed at this end of the roll whereby such articles are not subjected to excessive wrinkling as they lie on the work receiving surface.

14. In an ironing machine in combination, ironing members comprising a padded rotatable roll and a heated member, means for supporting 30 said heated member alongside of said roll having a part therebelow providing a work receiving surface for ironed articles, means for heating said heated member, means for supporting said roll solely from one end thereof, said roll supporting means comprising a gear case and a roll supporting member extending laterally therefrom and into said roll, said gear case having a rounded upper portion coaxial with the roll, and of smaller diameter than that of the roll and a portion therebeneath having a width not exceeding the diameter of the roll and power means, including gearing in said gear case, for 35 rotating the roll and moving one of said ironing elements into pressing engagement with the other, said power means and the means for supporting said ironing members being configurated and disposed so as to provide on the work receiving surface an unobstructed space of substantial width at and outwardly beyond the end of the roll adjacent to said gear case for the accommodation of articles ironed at this end of the roll whereby such articles are not subjected to 40 excessive wrinkling as they lie on the work receiving surface.

JOHN J. McCABE. 55
